AUTOMOBILE JACK

Millard B. Lucker, St. Joseph, Mich., assignor to
 Auto Specialties Manufacturing Company, St.
 Joseph, Mich., a corporation of Michigan

Application January 10, 1938, Serial No. 184,174

12 Claims. (Cl. 254—106)

This invention relates to automobile jacks of the type wherein a relatively long supporting member, preferably in the form of a rod or tube, is positioned in an upright manner and wherein a load supporting member, including a housing and an actuating member mounted thereon, is adapted to be moved vertically along the upright to raise or lower the load.

Among the objects of the present invention are to provide a simplified, more compact and more economical jack structure of the foregoing type; to provide a simplified housing, particularly a cast metal housing, for the jack; to provide a housing of integral, one-piece construction, preferably cast metal, wherein the opening in which the shiftable actuator is mounted is constructed and arranged to be utilized as an entry member for the holding and lifting cams and the springs, whereby the same may be assembled within the housing through this entry member, thereby eliminating additional openings in the housing to accomplish this assembly, and thereby eliminating the consequent weakening of the housing itself; to provide a more improved arrangement of the releasing cam in connection with the housing and particularly in connection and association with the opening in which the actuating lever is mounted so that the operation of the releasing cam is more simple and more easily and quickly effected; to provide an improved gear tooth construction operating connection between the lifting cam and the lifting actuator, specifically including the utilization of an involute gearing arrangement between these members, whereby to facilitate and improve the actuation of the lifting cam by the actuator while permitting at the same time their detachable connection for assembly purposes; to provide these and other objects of the invention as will be evident from a perusal of the following specification when taken in connection with the accompanying drawings, wherein:

Fig. 1 is a side elevational view of the preferred construction of the jack embodying the improved details of construction;

Figs. 2 and 3 are front and rear views corresponding thereto;

Figs. 4 and 5 are sections taken on lines 4—4 and 5—5, respectively, of Fig. 1;

Fig. 6 is a section of the jack showing one position of operation;

Fig. 7 is a similar view showing another position of operation;

Fig. 8 is a plan view of the releasing cam;

Fig. 9 shows a plan view of the actuating cam; Fig. 10 is a sectional view showing the manner of releasing the jack to permit it to come down;

Fig. 11 is a modified view showing a slightly different arrangement of interconnection between the actuating cam and the actuator;

Fig. 12 is still another modification of the actuating cam and the actuator;

Fig. 13 is yet another modification of the actuating cam and the actuator; and

Figs. 14 and 15 are modified constructions of the elongated supporting post or upright.

In general my invention comprises an elongated upright 2 preferably formed as a rod or tube and preferably of circular cross section, although this upright, as illustrated in Figs. 14 and 15, may be of polygonal cross section such as hexagonal cross section as shown at 4, or of square cross section, as shown at 6. This upright 2 is supported in any suitable base 8 with which it makes a detachable friction grip fit as at 10, whereby the elongated support 2 is held in general upright position. It will be noted that the opening in the base 8 is slightly larger than the diameter of the upright 2, whereby the upright may be tilted slightly away from the vertical to permit the upright to lean in any desired direction, while at the same time maintaining itself upright. The upper portion of this elongated support 2 is preferably peened over slightly as at 12 to form a stop or head which is adapted to contact with a portion of the housing herein-after described, to prevent detachment of the housing when in an uppermost position.

Cooperating with the elongated upright 2 is a housing member 14 of generally cylindrical cross section in part and preferably considerably elongated in the direction of the upright 2. This housing 14 is formed preferably as a one-piece or integral metallic casting and includes at its upper portion an elongated sleeve-like portion 16 which is of smaller diameter than the main body portion of the jack, which sleeve-like member is provided with an outstanding integral collar 18 forming a seat or abutment upon which is rotatably mounted a turnable load-supporting member or anvil 20 having a projecting prong 22 providing a suitably shaped holding recess 24. In the present instance this recess 24 is of general V-shape formation to receive the bottom portion of the bumper of an automobile. Obviously the shape of this saddle 20 may be made as desired to fit any object adapted to be lifted. In order to provide a convenient assembly, the upper por-

tion of the sleeve 16 is provided with a cast tit or lug 26, and the cylindrical portion 28 of the saddle 20 is provided with an outstanding vertical enlargement 30 which when said enlargement registers with the lug 26 will permit the saddle 20 to be slipped down over the lug 26 to assemble the saddle on the upper end of the sleeve 16. When so assembled, the enlargement 30 is then struck or deformed inwardly, as at 32, whereby permanently to unite the saddle on the sleeve 16 while permitting their relative rotation, so that the saddle may be freely turned in any direction to position it under the load without changing the position of the jack proper.

Somewhat below the sleeve portion 16 of the housing, the housing preferably tapers conically, as at 34, and a considerable distance down is provided with an inwardly projecting integral flange 36, the inner portion of which provides, in association with the upper head 12 of the elongated post 2, a stop member and in addition provides a bearing, if necessary, to prevent any lateral tilting between the housing and the post 2. By placing this member 36 a considerable distance inwardly and downwardly from the upper or top portion of the sleeve 16, it is possible to raise the housing along the post 2 so that the saddle 20 will extend a considerable distance beyond the topmost portion 12 of the post. In this position the inward flange 36 will contact the head 12 and prevent any further upward movement of the load-carrying member 20. The housing 14 below the partition 36 is formed as a main body portion and is provided with a substantially centrally located, horizontal, internal partition 38 which forms not only an abutment or seat for a spring but also provides a pivotal point for a cam. In the embodiment illustrated, it is preferred to place a releasing or holding cam 40 in the compartment 42 above the central partition 38. To this end the rear wall of the body portion 14 is provided with an opening 44, in the present instance preferably of rectangular formation, into which fits a substantially square lug 46 radially projecting from one side of the releasing cam 40. This cam has a main body portion preferably in the form of a washer, the washer at diametrically opposite sides having the lug 46 projecting therefrom and an oppositely extending lug 50 which is considerably longer and which is adapted to project outwardly of the housing as hereinafter described, whereby it may be contacted for shifting this cam to releasing position. The main body portion 48 of this cam is preferably formed or processed to provide opposite gripping jaws or portions 52 and 54, which portions by suitable processing, as set forth in certain of my prior pending applications, are brought in closely together whereby a slighter pivotal movement of the cam will effect a quicker gripping or releasing action. The specific construction of this cam is disclosed in certain of my prior pending applications.

This holding cam is normally held canted or tilted with respect to the elongated post 2 so as normally to grip the same by means of a coiled spring 56 which encircles the post 2 and presses against the under side of the cam and against the upper side of the internal partition 38.

An actuating cam is preferably disposed in a chamber 58 disposed between the central partition 38 and the bottom-most part of the housing 14 which is formed by inwardly turned walls 60 of the housing at its bottom, providing thereat an aperture 62 through which the elongated post 2 projects. These walls 60 provide at the bottom part of the housing a bearing and also a stop member for the post 2 so as to provide a bottom limit of travel for the jack as the portion 5 60 strikes the base 8. In the compartment 58 of the housing is mounted the actuating cam 64, comprising a washer-like element of the same general construction as cam 40, except that the cam 64 is provided with an upstanding toe or lug 66 on its upper surface, projecting in an upward direction and adapted to engage the under side of the central partition 38, as shown clearly in Fig. 6, to provide a tilting movement for this cam. In addition the cam is provided with an oppositely extending lug 68 which is adapted detachably to connect with an actuator as herein-after set forth. The cam is held in upper position, with the toe 66 against the under side of the partition 38, by means of a coiled spring 70 which has its bottom resting against the bearing surface 60 of the housing and its upper portion resting against the under surface of the cam 64.

The front of the housing is formed with an elongated opening 72 which extends substantially from the partition 36 to a point just a little above the bottom bearing 60. The walls of the housing for a considerable length of this opening extend outwardly in parallel, spaced apart relation as at 74, to provide two outstanding cheeks which are centrally bored as at 76 to receive a headed pin 78, which in turn passes through an opening in a lever actuator 80. The inner end of this lever actuator is provided with a detachable actuating connection with the actuating cam and the novel feature of this actuating connection resides in the fact that the inner contacting surfaces between the lug 68 and the actuating lever 80 are formed as an involute gear tooth construction, which permits of maximum ease of operation and effective movement of the actuating cam upon movement of the actuator 80, with minimum backlash. As shown in Fig. 6, the lug 68 of the actuating cam is formed as an involute gear tooth, while the inner end of the actuator 80 is provided with an interdental space of corresponding shape. In Fig. 11 the lug 82 of the actuating cam 64 is formed of involute construction and is also formed to provide an interdental space which engages two spaced teeth of involute construction, such as at 84, on the actuator 80. In Fig. 12 this construction is modified by showing only one involute gear tooth 84 cooperating with the involute interdental space on the actuator 64. In Fig. 13 I have shown a modified form of construction wherein the actuator 80 is provided with a lost-motion slot and pin connection with the actuating cam 64.

In assembling the improved jack, the two actuating cams and their coiled springs are first inserted through the elongated slot 72 in the front of the housing, any suitable jig or fixture being used to effect this, the springs serving to hold the cams in such position. The upright rod 2 is then inserted by placing the bottom-most end through the sleeve 16 and passing it downwardly through the openings in the cams and out through the opening 62 at the base of the housing, whereupon the rod is then connected to its base 8, whereby the cams and springs are held in position in the housing and whereby the rod 2 is assembled to the base so that the housing can not be taken from the base and so that the cams and springs can not then 70 75

be taken from the housing. Next the actuator 80 is inserted through the opening 72 so that the involute tooth gearing intermeshes. The pin 18 is then inserted through the opening 76 and a cotter pin 90 may then be inserted, or any other fastening means may be used whereby to hold the assembly in final organized relation.

The spring 56 of the holding cam 40 is arranged normally to project it upwardly with respect to the housing whereby it is tilted or canted so that the gripping jaws 52 and 54 will normally grip the rod. This cam is released by inserting the handle member 92, which detaches from the actuator 80 in the manner shown in dotted lines in Fig. 10, the upper or inner portion of this handle member underlying the upper partition 36 and the handle pressing down upon the long lug 50 of the releasing cam 40, whereby this cam is then shifted to such a position that the biting edges 52 and 54 are released, which will permit the housing to drop, it being presupposed that the actuator is in such position that the lifting cam is not then gripping the elongated post 2.

On the contrary, the actuator 80 is utilized for raising the housing along the stationary upright post 2. This is accomplished by shifting the actuator 80 from the position shown in Fig. 6 to that shown in Fig. 7, the cooperating spring 10 in connection with the lug 66 accomplishing the intermittent gripping and releasing of the rod by the actuator so that the housing upon vertical reciprocation of the actuator 80 pulls itself in a sort of monkey fashion up the rod 2, the holding cam permitting the housing to slip along the post 2 in an upward direction but preventing any downward releasing movement. For instance, with the actuator in the position shown in Fig. 6, by moving it to the position shown in Fig. 7 the upper tooth 81 of the actuator will press down upon the upper surface of the lug 68 of the actuating cam whereby to shift the actuating cam first to a substantially horizontal position.

It will be noted that in Fig. 6 the actuating cam is held normally somewhat tilted by the coiled spring 10 and by the lug 66 engaging the under side of the partition 38; hence the first movement of the tooth portion 81 pressing down against lug 68 is to slightly straighten out the cam, causing the teeth of the cam tightly to grip the upright rod 2. Due to the fact that the actuator is pivoted to the housing 18, and since the tubular upright 2 is stationary, this will cause the entire housing to be moved upwardly to such a point that the bottom bearing 60 will rise to a position shown in Fig. 7, thereby compressing the coiled spring 10. During this upward movement of the housing, the holding cam 40 will permit the housing to rise relatively to the stationary upright 2. Now, when the actuator is released, the spring 10 will force the actuator down and will force the actuating cam 64 up to a position again shown in Fig. 6, the actuating cam immediately assuming its tilted position. During this movement the holding cam will prevent the downward slipping of the housing relatively to the stationary upright post 2. Upon further actuation or repeated actuation of the actuator 80, this movement of the housing upwardly on the upright 2 is continued until the load is raised by the saddle 24.

By suitably elongating the tongue 50 of the releasing cam, I am enabled, upon the exertion of a relatively slight pressure on the upper sur-

face of this cam, to permit the housing freely to slide downwardly along the rod 2.

By the term "jack," as occurring in the title of invention, specification and claims, is meant any type of device having a pulling, pushing or supporting function, and the invention is not necessarily restricted to automobile jacks or even to jacks, unless the elements of a particular claim specifically otherwise limit the claim to a jack.

The claims of this case are directed to the gear-like connection between the actuating lever and the actuating cam, and to the release arrangement for the holding cam, claims to various other features of the construction shown being presented in copending applications of applicant, including applications, Serial No. 43,752, filed October 5, 1935; Serial No. 74,969, filed April 17, 1936; and Serial No. 101,693, filed September 21, 1936.

It is obvious that various changes may be made in the specific embodiments of the invention set forth for purposes of illustration without departing from the spirit of the invention. The invention is accordingly not to be limited to the precise embodiments shown and described, but only as indicated in the following claims.

Having thus described the invention, what I claim as new and desire to secure by Letters Patent of the United States is:

1. A lifting jack comprising a base, a load-lifting member, and means for moving the load-lifting member relative to the base comprising a housing and a friction clamp operating mechanism associated therewith, said operating mechanism comprising an actuating friction clamp and an operating lever pivotally mounted on the housing and having an operating connection with the actuating clamp, said operating connection comprising interengageable members on the actuating clamp and operating lever shaped into the form of involute gear teeth.

2. A lifting jack comprising a base, an up-standing shaft mounted thereon, a load-lifting housing longitudinally slidable on the shaft, and means for moving the housing along the shaft comprising a friction clamp operating mechanism, said operating mechanism comprising an actuating friction clamp and an operating lever pivotally mounted on the housing and having an operating connection with the actuating clamp, said operating connection comprising interengageable members on the actuating clamp and operating lever shaped into the form of involute gear teeth.

3. A lifting jack comprising a base, a load-lifting member, and means for moving the load-lifting member relative to the base comprising a housing and a friction clamp operating mechanism associated therewith, said operating mechanism comprising an actuating friction clamp and an operating lever pivotally mounted on the housing and having an operating connection with the actuating clamp, said operating connection comprising a pair of spaced projections on the operating lever and a member on the actuating clamp adapted to be engaged therebetween, the projections and member being shaped into the form of involute gear teeth.

4. A lifting jack comprising a base, an up-standing shaft mounted thereon, a load-lifting housing longitudinally slidable on the shaft, and means for moving the housing along the shaft comprising a friction clamp operating mechanism, said operating mechanism comprising an actuating friction clamp and an operating lever

- 5 pivotally mounted on the housing and having an operating connection with the actuating clamp, said operating connection comprising a pair of spaced projections on the operating lever and a member on the actuating clamp adapted to be engaged therebetween, the projections and member being shaped into the form of involute gear teeth.
5. A lifting jack comprising a base, a load-lifting member, and means for moving the load-lifting member relative to the base comprising a housing and a friction clamp operating mechanism associated therewith, said operating mechanism comprising an actuating friction clamp and an operating lever pivotally mounted on the housing and having an operating connection with the actuating clamp, said operating connection comprising a pair of spaced projections on the actuating clamp and a projection on the operating lever adapted to be engaged therebetween, said projections being shaped into the form of involute gear teeth.
6. A lifting jack comprising a base, a load-lifting member operatively supported by the base, and means for moving the load-lifting member relative to the base comprising a housing, a pair of friction clamps associated therewith, and a shaft extending through the housing and the clamps, one of said clamps being an actuating clamp and the other of said clamps being a holding clamp, an operating lever pivotally mounted on the housing and having an operating connection with the actuating clamp, said holding clamp being mounted within the housing and having a portion thereof fulcrumed on the housing and a projection extending outwardly through an opening formed through the housing, said housing opening being adapted to receive a release bar to be fulcrumed against a housing surface in the vicinity of the opening and against the holding clamp projection whereby to effect the release movements of the holding clamp, said housing surface and holding clamp projection being disposed on the same side of said shaft.
7. A lifting jack comprising a base, an up-standing shaft mounted thereon, a load-lifting housing longitudinally slideable on the shaft, and means for moving the load-lifting housing along the shaft comprising a pair of friction clamps associated with the housing and mounted on the shaft, one of said clamps being an actuating clamp adapted to move the housing in a lifting direction and the other of said clamps being a holding clamp adapted to prevent the movement of the housing in a release direction, an operating lever pivotally mounted on the housing and having an operating connection with the actuating clamp, said holding clamp being mounted within the housing and having a portion thereof fulcrumed on the housing and a projection extending outwardly through an opening formed through the housing, said housing opening being adapted to receive a release bar to be fulcrumed against a housing surface in the vicinity of the opening and moved in the direction in which the housing moves during its release movements into engagement with the holding clamp projection whereby to effect the release movements of the holding clamp, said housing surface and holding clamp projection being disposed on the same side of said shaft.
8. A lifting jack comprising a base, a load-lifting member operatively supported by the base, and means for moving the load-lifting member

relative to the base comprising a housing, a pair of friction clamps associated therewith, and a shaft extending through the housing and the clamps, one of said clamps being an actuating clamp and the other of said clamps being a holding clamp, an operating lever pivotally mounted on the housing and having an operating connection with the actuating clamp, a handle bar removably connected with the operating lever to effect the movements thereof, said holding clamp being mounted within the housing and having a portion thereof fulcrumed on the housing and a projection extending outwardly through an opening formed through the housing, said housing opening being adapted to receive said handle bar upon disconnection from the operating lever to be fulcrumed against a housing surface in the vicinity of the opening and against the holding clamp projection whereby to effect the release movements of the holding clamp, said housing surface and holding clamp projection being disposed on the same side of said shaft.

9. A lifting jack comprising a base, a load-lifting member operatively supported by the base, and means for moving the load-lifting member relative to the base comprising a housing, a pair of friction clamps associated therewith, and a shaft extending through the housing and the clamps, one of said clamps being an actuating clamp and the other of said clamps being a holding clamp, an operating lever pivotally mounted on the housing and having an operating connection with the actuating clamp, said holding clamp being mounted within the housing and having a portion thereof fulcrumed on the housing and a projection extending outwardly through an opening formed through the housing, said housing opening being arranged in the plane of operation of the operating lever and being adapted to receive a release bar to be fulcrumed against a housing surface in the vicinity of the opening and against the holding clamp projection whereby to effect the release movements of the holding clamp, said housing surface and holding clamp projection being disposed on the same side of said shaft.

10. A lifting jack comprising a base, an up-standing shaft mounted thereon, a load-lifting housing longitudinally slideable on the shaft, and means for moving the load-lifting housing along the shaft comprising a pair of friction clamps associated with the housing and mounted on the shaft, one of said clamps being an actuating clamp adapted to move the housing in a lifting direction and the other of said clamps being a holding clamp adapted to prevent the movement of the housing in a release direction, an operating lever pivotally mounted on the housing and having an operating connection with the actuating clamp, said holding clamp being mounted within the housing and having a portion thereof fulcrumed on the housing and a projection extending outwardly through an opening formed through the housing, said housing opening being arranged in the plane of operation of the operating lever and being adapted to receive a release bar to be fulcrumed against a housing surface in the vicinity of the opening and moved in the direction which the housing moves during its release movements into engagement with the holding clamp projection whereby to effect the release movements of the holding clamp, said housing surface and holding clamp projection being disposed on the same side of said shaft.

11. A lifting jack comprising a base, a load-lifting member operatively supported by the base, and means for moving the load-lifting member relative to the base comprising a housing and a pair of friction clamps associated therewith, one of said clamps being an actuating clamp and the other of said clamps being a holding clamp, an operating lever pivotally mounted on the housing and having an operating connection with the actuating clamp, said holding clamp being mounted within the housing and having a portion thereof fulcrumed on the housing and a projection extending outwardly through an opening formed through the housing, said housing opening being arranged in the plane of operation of the operating lever and being adapted to receive a release bar to be fulcrumed against the housing and against the holding clamp projection whereby to effect the release movements of the holding clamp, and resilient means engageable with the actuating clamp whereby to normally hold the operating lever in a position extending away from said housing opening.

12. A lifting jack comprising a base, an up-standing shaft mounted thereon, a load-lifting

housing longitudinally slidable on the shaft, and means for moving the load-lifting housing along the shaft comprising a pair of friction clamps associated with the housing, one of said clamps being an actuating clamp adapted to raise the housing and the other of said clamps being a holding clamp adapted to control the downward movement of the housing, an operating lever pivotally mounted on the housing and having an operating connection with the actuating clamp, said holding clamp being mounted within the housing and having a portion thereof fulcrumed on the housing and a projection extending outwardly through an opening formed through the housing, said housing opening being arranged substantially in the plane of operation of the operating lever and above the lever and adapted to receive a release bar to be fulcrumed against the housing and moved downwardly into engagement with the holding clamp projection whereby to effect the release movements of the holding clamp, and resilient means adapted to engage the actuating clamp and normally hold the operating lever extending downwardly.

MILLARD B. LUCKER. 25
